Nathaniel J. Myerth
The Schedule referred to in these Letters Patent, and making part of
the same, containing a description in the words of the said Nathaniel
J. Myerth himself, of his improvement in the manner of cutting ice,
together with the machinery or apparatus therefor.

- 1st Two bars of iron or other material, secured to each other by cross-bars, the two bars mentioned to be of such distance apart as the dimension of the ice is required to be.
- 2nd On each outside bar is bolted a plate of iron as long as the bar, and at right angles with the cross-bars - these plates to be so bolted to the bars, as to project three inches each on one side of the bars to which they are bolted, and one of them to project on the other side of the bar, two inches, - the other, one inch. These projections may be varied according to the desired depth of the cast.
- 3rd These plates, both on the upper side, and on the under side of the bars, are to be cast at four equidistant points each, at an angle of forty-five degrees, or thereabouts, to the bar, thereby forming a cutting point of forty-five degrees or thereabouts; - to this point is welded a piece of steel to form the chisel. The over end of the plates to be of the before specified width from the bar, but to diminish toward the front, and one fourth of an inch at each point, thereby giving each succeeding point an over cast of one fourth of an inch deeper than its predecessor.

"Oath sworn 24th October 1860

- 4th The smooths, by which the ships sail from the ice by the chisel are discharge, are made similar to that of a carpenter's plough.
- 5th To the middle of the front edge bar is fixed a ring, for the purpose of attaching a straight chain, to which the horse that draws the cutter is to be harnessed.
- 6th This first part of the apparatus for cutting ice is called the cutter, and is used as follows. The cutter is laid on the ice with the three inch side of the plates downward, and drawn forward in a straight line as far as is required, then making two grooves of an inch deep. The horse is then turned about and the cutter turned over, so that the two inch side of the plate shall be in one of the first grooves cut, and the one inch side on the ice; and as the cutter is drawn forward, the two inch side makes one of the first grooves an inch deeper and the one inch side forms a new groove of an inch deep. Proceed in this manner until as many grooves are cut as are wanted; then turn the cutter over upon the three inch side, go over the whole again with this side, and they are finished. Repeat the same process at right angles with the first grooves, and the operation with this part of the apparatus is finished.

Part second of apparatus for cutting ice.

- 1st Two spur wheels, about three feet six inches, more or less, in diameter, connected together by an axle-tree of iron, or other material, from the centre of each to the other fixed immovable in each.
- 2nd A pair of gills proceeding from the axle-tree and secured to it by a pair of composition boxes, admitting the axle-tree to turn in them.
- 3rd A cog wheel, about three feet two inches in diameter, more or less, fixed to the centre of the axle-tree, so as to be incapable of turning, except with the axle-tree.
- 4th A pair of flounders attached to the axle-tree, in the same manner as the gills, so as to admit of the motion of the axle-tree in

thorn; these handles to be placed one on each side of the cog-wheel in the center of the yoke-tree, and to be connected together by a permanent bar at a suitable distance from the yoke-tree.

5th. Two cog-wheels, about four inches diameter, more or less, one of which to work on the large cog-wheel, and the other to work on the one so working, and both to be secured by pintles passing through the handles; the small cog-wheel not working on the large cog-wheel to have secured beside it, a circular saw, about two and a half feet diameter, more or less.

6th. The proportion between the large & small cog-wheels is varied to obtain greater or less velocity for the saw as may be wanted.

This part of the apparatus for cutting ice is called the saw-mill and is used as follows.—Put the saw into one of the outer side grooves made by the cutter; drive the horse forward, following the groove made by the cutter; at the same time a man who manages the handles, presses them down as much as the strength of the horse will admit of. This operation is followed back and forth until the ice is cut through. The same is done with the outer parallel groove on the opposite side of the horse, and also on one of the end grooves running at right angles with these. By thus pressing the ice on three sides of the flat or work marked by the cutter is cut through. When this is done take an iron bar, one end of which is wide and fitted to the groove, and the other end of which is sharpened as a chisel and insert the end which is fitted to the groove into the groove next to and parallel with the end groove which is cut through; press lightly in several places, then more strongly, until the ice is broken off; then strike lightly with the chisel end of the bar, into the edge grooves of the piece split off, and it easily separates into square pieces. These proceed with the whole flat knocked out by the cutter. It is claimed as new, to cut ice of a uniform size by means of an apparatus, worked by any other power than human. The invention of this art, as well as of the particular method of the application of the principle, are claimed by the subscriber.
